UNITED STATES PATENT OFFICE.

BERNARD D. WILLIS, OF OAK PARK, ILLINOIS, ASSIGNOR, BY MESNE ASSIGNMENTS, TO AUTOMATIC ELECTRIC INC., OF CHICAGO, ILLINOIS, A CORPORATION OF DELAWARE.

AUTOMATIC TELEPHONE SYSTEM.

Application filed March 10, 1922, Serial No. 542,673. Renewed August 3, 1927.

The present invention relates in general to multi-office telephone systems comprising both manual and automatic offices, but is concerned more particularly with the inter-
5 connecting trunks in such a system that carry traffic from a manual to an automatic office; and the principal feature relates to the prevention of preliminary impulses which are likely to occur when an operator
10 plugs into a jack with which there is connected a trunk leading to an automatic switch.

Other objects which have to do with the carrying out of the general scheme will be
15 pointed out and explained fully hereinafter.

Referring now to the drawings comprising Figs. 1, 2, and 3, when laid out in order with the corresponding lines at the end thereof in alignment, they represent by means of the
20 usual circuit diagrams a sufficient amount of apparatus for a complete connection from a calling substation A in a manual office to a called substation A' in a private branch exchange which private branch exchange is associated with an automatic office. The apparatus shown in Fig. 1, together with the manual equipment in Fig. 2 comprising the operator's trunk circuit O', is assumed to be located in the manual office; the remaining
25 equipment shown in Fig. 2 in the automatic office; and the equipment in Fig. 3 in the private branch exchange.

The equipment shown in Fig. 1 comprising the substation A and associated equipment and the operator's cord circuit O is manual equipment of a well known type. However, the calling end of the cord circuit O is slightly modified as will be pointed out fully hereinafter.

40 The operator's trunk circuit O', Fig. 2, is provided for the purpose of permitting a "B" operator to set up an automatic connection after she has been signalled and the number has been repeated to her by the
45 "A" operator.

The automatic selectors E and E', Fig. 2, which are denoted by the dotted rectangles bearing those reference characters, are assumed to be of the well known vertical and rotary type having their bank contacts arranged in horizontal rows or levels. The circuits of these switches are well known and consequently do not need to be shown.

The connector H is mechanically identical

with either of the selectors E and E'. Most 55 of the circuits of this connector, however, have been omitted, only the line, release, and back bridge relays being shown.

The line switch C is provided to take care of calls incoming from the branch exchange 60 over the trunk comprising conductors 52 and 53. This line switch is of the well known rotary type of which the wipers have no normal position and move in a forward direction only. The circuits of this switch 65 are fully shown and will be described hereinafter.

Automatic switches similar to the selectors E and E', the connector H and the line switch C, referred to above, are shown and 70 described in Automatic Telephony which is a book written by Smith and Campbell. This book is published by McGraw-Hill Book Company, New York, N. Y.

The operator's trunk circuit T, Fig. 3, 75 is provided with the line lamp L³ and associated equipment for receiving incoming calls and is provided with the calling device key K² which is used to connect up the common calling device S' when an outgoing call is being made. The operations of the various circuits involved will be explained in detail hereinafter.

The operator's cord circuit O² is a manual 80 cord circuit of the well known double plug type. The circuits of this cord circuit are shown complete and will be described fully hereinafter.

The substation A' is an ordinary manual 85 substation and is identical with the substation A, Fig. 1.

The apparatus, having been described in general, will now be described in connection with a detailed description of its operation. For this purpose it will be assumed that the 90 subscriber at substation A, Fig. 1, in the manual office desires to converse with the subscriber at substation A', Fig. 3, in the private branch exchange, which private branch exchange is a branch of the automatic office. When the receiver is removed at substation A, a circuit is closed over line conductors 11 and 12 for line relay 14 which, upon energizing, closes a circuit for the line lamp L.

100 The operator, upon noting the lighted condition of the lamp L, inserts the answering plug of an idle cord circuit, the plug P

of the cord circuit O for example, into the jack J, whereupon cut off relay 13 energizes in series with supervisory lamp L', thereby clearing the calling line, whereupon the lamp L becomes extinguished. Supervisory relay 15, upon energizing over the calling subscriber's loop, places a shunt around the supervisory lamp L', thereby preventing the said lamp from becoming lighted at this time.

The operator now throws her key K, which is a combined listening and ringing key, into listening position, thereby connecting up the conductors from her head set with the right hand strands of the cord circuit. After obtaining the desired number from the calling subscriber by conversing with him in the usual manner, the operator inserts the plug P' into the jack J', after having ascertained that the associated trunk is idle by touching the tip of her cord with the sleeve of the jack. When the tip of the plug P' comes into engagement with the tip spring of the jack J', the following circuit is closed: from ground by way of the tip of the plug P', corresponding contact of the jack J', conductor 25, relay 28 at the "B" operator's position, Fig. 2, armature 39 and its resting contact, and resistance 36 to battery. Relay 28, upon energizing, removes the short circuit from around sleeve relay 29 at armature 35, whereupon sleeve relay 29 energizes in series with resistance 34 and in series with relay 17 of the cord circuit O. Relay 17 in the cord circuit O, upon energizing, closes a circuit for the supervisory lamp L', and relay 29 in the trunk circuit O', upon energizing, opens at armature 38 another point in the shunt which was around it, prior to the energization of relay 28, at the same time closing a circuit for the signal lamp L' by way of armature 41 and its resting contact, whereupon the lamp L' becomes lighted. As a further result of the energization of relay 29, it disconnects relay 28 from battery at armature 39 and connects it by way of armature 42 and its resting contact and the condenser shown to the right hand winding of the tone machine TM. When this occurs relay 28 deenergizes and the "A" operator, who still has her listening key thrown, hears the tone produced by the tone machine TM. As a still further result of the energization of sleeve relay 29, it closes at armature 40 a bridge across the conductors of the trunk extending to the selector E in the distant automatic office as follows: from the lower conductor of the trunk extending to the selector E, by way of the normally closed contacts controlled by spring 48 of the key K', armature 40 and its working contact, polarized relay 31, and the normally closed contacts controlled by spring 47 of the key K' to the upper conductor of the trunk extending to the selec-

tor E. In response to the closing of this bridge, the line and release relays (not shown) of the selector E energize, thereby preparing the switch for operation in the usual manner. Polarized relay 31 energizes but in a direction opposite to that in which it must energize to operate spring 43.

Before going further with the operation, a few points in connection with the arrangement to prevent preliminary impulses will be considered. As pointed out in the preceding paragraph, a bridge is closed across the conductors of the trunk extending to the selector E in the automatic exchange at armature 40 of sleeve relay 29 upon the energization of that relay. This relay, as explained, is energized over the sleeve conductor of the jack J' and, since there is a battery potential upon the ring contact of the plug P' as well as upon the sleeve contact thereof, the said sleeve relay 29 might be energized and deenergized, thereby delivering a preliminary impulse to the selector E, as the plug is being inserted into the jack if it were not for the fact that the said sleeve relay 29 is normally short circuited, as shown. Obviously, however sleeve relay 29, being normally short circuited, does not energize until the tip contact of the plug comes into engagement with the tip contact of the jack at which time the sleeve contact of the plug will have firmly engaged the sleeve contact of the jack.

To continue with the operation, the "B" operator, upon observing the lighted condition of the lamp L', operates her key K' which is a combined listening and calling device key, thereby connecting up her head set in the manner shown so as to enable her to converse with the "A" operator. As a further result of the key K' being operated, it closes at its upper pair of contacts a circuit for relay 30. Relay 30, upon energizing, opens the circuit of the signal lamp L' at armature 41, whereupon the said lamp becomes extinguished, and at the said armature 41 and its working contact closes a locking circuit for itself which circuit includes armature 38 and its working contact. As a further result of the energization of relay 30, it disconnects the tone lead of the tone machine TM from the trunk, thereby apprising the "A" operator immediately of the fact that the "B" operator has responded. As a still further result of the key K' being operated it closes at its lower pair of contacts a circuit for relay 33, which circuit includes the resting contact of armature 37 and said armature. Relay 33, upon energizing, closes a locking circuit for itself at armature 46 independent of the key K', and at armature 45 places impedance 32 in bridge of the conductors 25 and 27. When this occurs supervisory relay 16 of the cord circuit O, upon energizing, places a shunt

around the marginally adjusted relay 17, whereupon the said relay deenergizes, thereby extinguishing the supervisory lamp L^2 which gives the "A" operator answering supervision. As a further result of the key K' being thrown, it places the calling device S and the release push button R in bridge of the conductors of the trunk extending to the selector E , at the same time removing the bridge including polarized relay 31, thereby placing the line relay of the selector E under the control of the calling device S .

The "A" operator, upon noting the discontinuance of the tone, which tone is disconnected when the key K' is thrown, as described, repeats the desired number to the "B" operator, and, upon being confirmed by the "B" operator that the latter has heard the number correctly, she restores her listening key K to normal. It will be noted that the calling subscriber is able to hear the "A" operator repeat the number to the "B" operator and consequently if the "A" operator has not heard the number correctly or if for any reason she does not give the correct number to the "B" operator, he may make the desired correction.

The "B" operator, after having been informed of the desired number, manipulates the calling device S in accordance with the various digits thereof, thereby operating the selectors E and E' and the connector H with the result that the wipers of the latter are brought into engagement with an idle trunk leading to the desired branch exchange, which trunk it will be assumed is the trunk shown in the drawings and comprising conductors 52 and 53. It will be noted that if the "B" operator makes a mistake while dialing the number she may release the partly established connection by operating the release push button R and then proceed to dial the number over again. The "B" operator restores the key K' to normal after she has finished dialling the number.

When the private wiper of the connector H comes into engagement with the test contact of the trunk extending to the private branch exchange, a circuit is closed over private normal conductor 54 for switching relay 56 and stepping magnet 57 of the line switch C in series. Stepping magnet 57 does not energize over this circuit on account of the high resistance of switching relay 56 and the latter, upon energizing, disconnects its armatures from their resting contacts, thereby clearing the called trunk of its battery and ground connections, but owing to a mechanical interlocking device (not shown) between the armature of this relay and the armature of line relay 55, the said switching relay 56 is not able to operate fully and consequently, since its armatures do not come into engagement with their working contacts, the switch wipers are not connected up.

In the connector H , the switching relay thereof, upon energizing, connects up the line wipers to the ring cut off relay (not shown), whereupon ringing current is projected out over the trunk to the private branch exchange. This ringing current is repeated through the repeating coil in the trunk circuit T and operates relay 66 through the medium of its bridged winding. Relay 66, upon energizing, closes a locking circuit 75 for itself in multiple with the line lamp L^3 at armature 72, whereupon the said line lamp L^3 becomes lighted. As a further result of the energization of relay 66, it prepares a circuit for sleeve relay 67 at armature 73.

The branch exchange operator, upon noting the lighted condition of the line lamp L^3 , inserts the plug of an idle cord circuit, the plug P^2 of the cord circuit O^2 for example, into the jack J^2 , thereby completing a circuit for sleeve relay 67 in series with supervisory lamp L^4 . Sleeve relay 67, upon energizing, closes a locking circuit for itself independent of relay 66 and opens the locking circuit of relay 66 and the circuit of line lamp L^3 at armature 71, whereupon the said relay 66 deenergizes and the line lamp L^3 becomes extinguished. As a further result of the energization of relay 67, it disconnects the left hand winding of ring up relay 66 from in bridge of the tip and ring conductors of the jack J^2 at armature 70, and at armature 69 bridges the polarized relay 65 around the condenser associated with the left hand winding of the repeating coil. When this occurs, the ring cut off relay of the connector H (not shown) energizes, thereby connecting the wipers of the said connector to back bridge relay 66'. Polarized relay 65 in the trunk circuit T , upon energizing, operates spring 68, thereby bridging the resistance 74 around the condenser associated with the right hand windings of the repeating coil. When this occurs, supervisory relay 75 of the cord circuit O^2 , upon energizing, places 116 a shunt around the supervisory lamp L^4 , thereby preventing the said lamp from becoming lighted at this time.

In the connector H back bridge relay 66', upon energizing over the called trunk, reverses the incoming trunk conductors as regards their connection with the windings of line relay 50. When this occurs, polarized relay 31 in the "B" operator's trunk circuit O' energizes in the opposite direction, thereby bringing spring 43 into engagement with its working contact. Spring 43, upon coming into engagement with its working contact, bridges relay 28 across the conductors 25 and 27 by way of the working contact of armature 39 and said armature. Relay 28, upon energizing, opens the circuit of relay 33 at armature 37. Relay 33, upon deenergizing, opens a further point in its circuit at armature 46, and at armature 45 removes

the impedance 32 from in bridge of the conductors 25 and 27, leaving the said conductors bridged by relay 28 only. It will be noted that this bridge, which controls the supervisory relay 16 of the cord circuit O, is controlled by the polarized supervisory relay 31.

The calling subscriber may now converse with the branch exchange operator and the operator, upon learning with which line he desires to be connected, inserts the calling plug P³ into the jack J³ of the desired line, whereupon supervisory lamp L⁵ becomes lighted in series with the cut off relay associated with the said jack J³ and the said cut off relay, upon energizing, clears the called line of its battery and ground connections.

The operator now signals the called subscriber by throwing her key K³ to ringing position momentarily, and when the called subscriber responds by removing his receiver supervisory relay 76, upon energizing, places a shunt around supervisory lamp L⁵, whereupon the said lamp becomes extinguished, thereby giving the operator answering supervision. The calling and called subscribers may now converse with each other in the usual manner, the talking circuits being outlined by the heavy conductors, and when the conversation is completed the two subscribers replace their receivers.

When the receiver is replaced at substation A', the circuit of supervisory relay 76 is opened and the said relay, upon deenergizing, removes the shunt from around the supervisory lamp L⁵, whereupon the said lamp becomes lighted.

When the receiver is replaced at the calling substation A, the circuit of supervisory relay 15 is opened and the said relay, upon deenergizing, removes the shunt from around supervisory lamp L¹, whereupon the said lamp becomes lighted.

The branch exchange operator now has a disconnect signal from the called subscriber and the "A" operator in the manual office has received a disconnect signal from the calling subscriber. Assuming that the branch exchange operator pulls down the connection first, back bridge relay 66' of the connector H is deenergized, its circuit being opened in a manner to be explained fully hereinafter, and reverses the incoming trunk conductors back to normal. When this occurs, the polarized supervisory relay 31 in the "B" operator's trunk circuit O' is energized in the opposite direction, thereby permitting spring 43 to move out of engagement with its working contact, thereby removing relay 28 from in bridge of the trunk conductors 25 and 27. When this occurs, supervisory relay 16 in the cord circuit O, upon deenergizing, removes the shunt from around relay 17, whereupon the said relay

energizes, thereby closing a circuit for the supervisory lamp L². When the said lamp L² becomes lighted the operator pulls down the connection. In the present case, however, since the "A" operator in the manual office is handling the call and since the disconnect signal which she receives comes from the calling subscriber, it is reasonable to assume that she will pull down the connection before the branch exchange operator takes down her cord.

With the assumption as noted above, the supervisory lamp L¹ of the cord circuit O becomes extinguished and the cut off relay 13 deenergizes when the plug P is removed from the jack J, and when the plug P' is removed from the jack J', the circuit of sleeve relay 29 and relay 28 in the "B" operator's trunk circuit O' is opened, whereupon the relays 28 and 29 deenergize. Relay 29, upon deenergizing, opens the bridge across the conductors of the trunk extending to the automatic switches, whereupon polarized relay 31 deenergizes and the automatic switches are released in the usual manner.

In response to the release of the connector H, the circuit of switching relay 56 of the line switch C is opened and the said relay, upon deenergizing, connects up line relay 55 to the trunk conductors 52 and 53. When this occurs, line relay 55 energizes over the bridge across the trunk conductors in the private branch exchange, whereupon the line switch C operates in the usual manner to select an idle trunk. This, however, is merely an incidental operation at this time. In the private branch exchange, polarized relay 65 is energized in the opposite direction upon the connecting up of the line relay of the line switch C in place of the back bridge relay 66 of the connector H, owing to the conductors 52 and 53 being reversed at the banks of the said connector H. When this occurs, spring 68, upon moving out of engagement with its associated contact, opens the circuit of supervisory relay 75 in the cord circuit O² and the said relay, upon deenergizing, removes the shunt from around supervisory lamp L⁴, whereupon the said lamp becomes lighted.

The private branch exchange operator upon noting the lighted condition of the lamps L⁴ and L⁵, pulls down the connection. When the plug is removed from the jack J³ supervisory lamp L⁵ becomes extinguished and the cut off relay associated with the said jack J³ deenergizes. When the plug is removed from the jack J² supervisory lamp L⁴ becomes extinguished and sleeve relay 67 deenergizes, thereby removing polarized relay 65 from in shunt of the condenser associated with the left hand windings of the repeating coil. When this occurs, the trunk which has been seized by the line switch C, Fig. 2, is freed in the usual manner. The entire

connection is now released and the apparatus used therein is restored to normal.

We shall assume now that the subscriber at substation A' desires to be connected with some subscriber in the automatic office. When the receiver is removed at the substation A' the line lamp L⁶ becomes lighted in the usual manner, whereupon the operator responds by inserting the answering plug of an idle cord circuit, the plug P² of the cord circuit O² for example, into the jack J². This operation, it will be noted, is identical with that when the subscriber at substation A removes his receiver to make a call.

The operator, after having been apprised of the desired number inserts the calling plug P³ into the jack J². In this case, it will be noted that sleeve relay 67, which controls the bridge across the trunk conductors 52 and 53, is normally disconnected from ground and consequently there is no possibility of a preliminary impulse being caused when the operator plugs into the associated jack J². Upon the plug P³ being fully inserted into the jack J², a circuit is closed over the tip and ring contacts of the said plug P³ and the tip and ring contacts of the jack J² for the left hand winding of relay 66. Relay 66, upon energizing, completes at armature 73 a circuit for sleeve relay 67 in series with supervisory lamp L⁵, whereupon the supervisory lamp L⁵ becomes lighted and sleeve relay 67, upon energizing, closes a locking circuit for itself at armature 71. As a further result of the energization of sleeve relay 67, it opens at armature 70 the circuit of the left hand winding of relay 66, whereupon the said relay 66 deenergizes. As a still further result of the energization of sleeve relay 67, it closes a bridge across the trunk conductors 52 and 53 at armature 69, the said bridge including polarized relay 65 and the left hand windings of the associated repeating coil. Relay 65 becomes energized in series with line relay 57 of the line switch C, Fig. 2, but in a direction which is opposite to that in which it must energize to bring the spring 68 into engagement with its working contact.

In the automatic office, line relay 55 of the line switch C, upon energizing, places ground upon private normal conductor 54 at armature 59, thereby closing a circuit for switching relay 56 and stepping magnet 57 in series, and at armature 58 connects test wiper 64 to the above circuit at a point between switching relay 56 and stepping magnet 57.

The operation now depends upon whether the trunk, upon which the wipers 63-65, inclusive, of the line switch are standing, is busy or idle. If it is idle, switching relay 56 energizes immediately, but if it is busy, switching relay 56 is short circuited by the ground potential which is present upon the

test contact thereof and the switch wipers are advanced step by step by the buzzer like action of stepping magnet 57. When an idle trunk is reached, there is no ground potential upon the test contact thereof and switching relay 56, being no longer short circuited, energizes in series with stepping magnet 57. Stepping magnet 57, however, does not energize at this time on account of the high resistance of switching relay 56. As a result of the energization of switching relay 56, the private normal conductor 54 is connected with the release trunk conductor of the seized trunk at armature 61, and at armatures 60 and 62 battery and ground are removed from the trunk conductors and the said trunk conductors are extended by way of wipers 63 and 65 to the windings of the line relay of the switch (not shown) associated with the seized trunk. When this occurs, the switch associated with the seized trunk is prepared for operation in the usual manner and the usual holding circuit is closed for switching relay 56 of the line switch C.

In the branch exchange, the operator, after having inserted the plug P² into the jack J², throws the calling device key K², thereby shifting the bridge across the conductors 52 and 53 so as to include the common calling device S' and the release push button R' instead of the left hand windings of the repeating coil and polarized relay 65.

The operator now proceeds to dial the various digits in the desired number in the usual manner, thereby causing the connection to be extended to the desired line and causing the called subscriber's bell to be rung in the well-known manner. After having finished dialling the number, the operator restores the key K² to normal, thereby connecting up the bridge which includes polarized relay 65 and disconnecting the calling device S' from in bridge of the conductors 52 and 53.

When the called subscriber answers, the consequent reversal of battery, which occurs in the well-known manner by the pulling up of the back bridge relay of the connector, causes the polarized relay 65 of the trunk circuit T to be energized in the opposite direction, thereby closing a bridge across the tip and ring conductors of the jack J² at spring 68 and its working contact, which bridge includes the right hand windings of the repeating coil and resistance 74. Supervisory relay 76 in the cord circuit O, upon energizing in response to the closure of this bridge, places a shunt around supervisory lamp L⁵, whereupon the said lamp becomes extinguished, thereby giving the operator answering supervision. The calling and called subscribers may now converse with each other in the usual manner, the talking circuits that are shown being

outlined by the heavy conductors, and when the conversation is completed they both replace their receivers. When the receiver is replaced at substation A' the supervisory lamp L⁴ becomes lighted in the usual manner.

When the receiver is replaced at the called substation in the automatic office, the back bridge relay of the connector in use de-energizes, thereby reversing the current flow in the established connection back to normal, whereupon the polarized relay 65 in the trunk circuit T, opens the bridge across the tip and ring conductors of the jack J² at spring 68. When this occurs, supervisory relay 76 in the cord circuit O deenergizes, and the lamp L⁵ becomes lighted.

The operator, upon noting the lighted condition of the lamps L⁴ and L⁵ pulls down the connection. When the plug P² is removed from the jack J³ supervisory lamp L⁴ becomes extinguished and the cut off relay of the said jack deenergizes. When the plug P³ is removed from the jack J² supervisory lamp L⁵ becomes extinguished and sleeve relay 67, upon deenergizing, opens the bridge across the trunk conductors 52 and 53, whereupon the automatic switches are restored to normal in the usual manner.

30 The entire connection is now released and the apparatus used therein is restored to normal.

The various features of the invention, having been described and ascertained, will 35 now be pointed out in the appended claims.

What is claimed is:

1. In a telephone system, a trunk terminating at one end at an operator's position and at the other end in an automatic switch, 40 a spring jack associated with said trunk at said operator's position, said spring jack having a pair of line conductors and a test conductor, a plug having conductors connected therewith adapted to connect with said conductors of said jack when said plug is inserted into said jack, a first relay bridged across said line conductors, a second relay, normally inoperative, connected with said test conductor, circuit connections 45 for operating said first relay over said line conductors in series when said plug is inserted into said jack, means controlled by said first relay for rendering said second relay operative, and means controlled by 50 said second relay for closing a control circuit for said automatic switch over said trunk.

2. In a telephone system, an "A" operator's position, a "B" operator's position, 55 means whereby an operator at said "A" position can extend a connection to said "B" position, means including automatic switching mechanism whereby an operator at said "B" position can extend the connection on 60 toward a called subscriber, means responsive

to the connection being extended to said "B" position for signalling the operator thereat and for giving the operator at said "A" position a distinctive tone, and means for removing said tone upon the response of the 70 operator at said "B" position.

3. In a telephone system, two manual switchboards, a trunk line connecting said switchboards, a signal at the second switchboard, a signalling machine, means for operating said signal and for connecting said machine to the trunk line when the same is taken for use by an operator at the first switchboard, the said machine being effective to transmit an audible signal to the calling operator, a listening key at said second switchboard, and means responsive to the actuation of said key for disconnecting said machine from the trunk line to notify the calling operator that the other operator is 85 listening.

4. In a telephone system, a trunk line extending from a jack to an automatic switch, a relay for closing a bridge across said trunk line to operate said switch, a plug 90 adapted to be inserted in said jack, a circuit for said relay including the sleeve of said plug, a second relay for closing said circuit, and a circuit for said second relay including the tip of said plug.

5. In a telephone system, a trunk line extending from a jack to an automatic switch, a relay for closing a bridge across said trunk line to operate said switch, a plug adapted 100 to be inserted in said jack, a circuit for said relay including the sleeve of said plug, a second relay for closing said circuit, a cord circuit terminating in said plug, and a circuit for said second relay including the tip and ring strands of said cord circuit in 105 series.

6. In a telephone system, a manual exchange and an automatic exchange, a dialling operator's position at the manual exchange, a trunk line coming from the subscriber's switchboard in the manual exchange and extending through the dialling position to an automatic switch in the automatic exchange, means whereby a manual exchange operator can signal the dialling operator when an automatic exchange connection is wanted, a supervisory signal controlled over the two sides of said trunk line 110 in series by the response of the dialling operator to notify the manual exchange operator thereof, means whereby the dialling operator can control said switch and other switches to complete the desired connection, and means whereby the dialling operator can disconnect herself from the trunk line before the called subscriber answers without 115 affecting said supervisory signal.

7. In a telephone system, a trunk line comprising two inductively connected sections. 120 operator's equipment at the junction of said

sections, a relay energized responsive to the answering of a call over the first section of said trunk line by the operator, a locking circuit for said relay, contacts on said relay 5 for closing a bridge across the first section, means controlled by the operator for completing the connection over the second section, a relay controlled by the response of the called party for closing a second bridge 10 across the first section, a relay in said second bridge, and contacts on said last mentioned relay for opening said locking circuit.

8. In a telephone system, manual switchboards, a trunk line connecting said switchboards, a signal at one of said switchboards, means for operating said signal, a relay for connecting said signal operating means to the trunk line when the same is taken 15 for use by an operator at one of said switchboards, a listening key at another of said switchboards, and means responsive to the actuation of said key for disconnecting said signal operating means from the trunk line 20 to notify the calling operator that the other operator is listening.

9. In a telephone system, a trunk line connecting two exchanges, a relay having one terminal connected to one conductor of said 30 trunk line and the other terminal connected to battery, means for establishing a circuit for said relay including only one talking conductor of said trunk line and ground return when a call is being extended over said 35 trunk, means for establishing a metallic circuit for said relay including both conductors of said trunk line, call and supervisory signals, means for controlling said relay over one of its circuits to control said call signal, and means for controlling said relay over the other of its circuits to control said 40 supervisory signal.

10. In a telephone system, a two way trunk circuit terminating at one end in a 45 jack and at the other end in a set of bank contacts, an automatic switch for extending a calling line by way of said contacts to said trunk circuit to extend a call there over in one direction, said switch including means 50 for applying ringing current to said trunk circuit, a plug ending cord circuit for extending a calling line to said trunk circuit by way of said jack to extend a call over said trunk circuit in the other direction, said 55 cord circuit including means for supplying talking battery, and a relay normally bridged across said trunk circuit, said relay energized by said ringing current responsive to the extension of a calling line in said 60 one direction and energized by said talking battery responsive to the extension of a calling line in said other direction.

11. In a telephone system, a two way trunk circuit terminating in a jack and bank 65 contacts, automatic switches for connecting

a calling line by way of said contacts to said trunk circuit at one end, a plug ending cord circuit for connecting a calling line to said trunk circuit by way of said jack at the other end, a relay normally bridged across said 70 trunk circuit and energized responsive to the connection of a calling line to said trunk circuit at either end, a call lamp associated with said trunk circuit and lighted by said relay responsive to a connection established 75 at one end, and a second relay in said trunk circuit for preventing said lamp from being lighted by said first relay responsive to a connection established at the other end.

12. In a telephone system, two manual 80 switchboards, a trunk line including a sleeve conductor connecting said switchboards, a call lamp at the second switchboard, a relay at the second switchboard connected to the sleeve conductor of said trunk line and 85 normally shunted, a cord circuit at the first switchboard for extending a connection to said trunk line, and means responsive to the extension of said connection for removing said shunt and allowing said relay to energize 90 to light said lamp.

13. In a manual to automatic trunk circuit, a source of signalling current, a relay energized responsive to the seizure of the trunk at the manual end for connecting said 95 source to the trunk, a dialling key, and a second relay energized responsive to the actuation of said key for disconnecting said source from the trunk.

14. In a manual to automatic trunk circuit, a source of signalling current, a relay energized responsive to the seizure of the trunk at the manual end for connecting said source to the trunk, a dialling key, a second 105 relay energized responsive to the actuation of said key for disconnecting said source from the trunk, and a locking circuit for said second relay controlled by said first relay.

15. A manual to automatic trunk extending from a jack to an automatic switch, a relay energized over the sleeve of said jack, a call signal operated over a circuit controlled by said relay, a dialling key inserted in said trunk, a second relay energized 110 responsive to the actuation of said dialling key, and contacts on said second relay for substituting the said second relay for the said signal in the circuit controlled by the first relay whereby the signal is deactuated 115 and the second relay is locked under control of the first relay.

16. A manual to automatic trunk extending from a jack to an automatic switch, condensers in series with the talking conductors of the trunk between the jack and the automatic switch, means responsive to the establishment of a connection to the trunk by way of the jack for establishing a direct 125 current bridge across the ends of the talking 130

- conductors terminating in the automatic switch, an operator's headset and dialling equipment, a combined listening and dialling key, for splitting the talking conductors at a point between the condenser and the automatic switch, means controlled by said key for connecting the dialling equipment across the end of the trunk terminating in the automatic switch to operate the switch and for connecting the operator's headset across the other end of the trunk, and means controlled by the key for establishing a direct current bridge across the end of the trunk terminating in the plug.
17. A manual to automatic trunk extending from a jack to an automatic switch, condensers in series with the talking conductors of the trunk between the jack and the automatic switch, means responsive to the establishment of a connection to the trunk by way of the jack for establishing a direct current bridge across the ends of the talking conductors terminating in the automatic switch, an operator's headset and dialling

equipment, a combined listening and dialling key, for splitting the talking conductors at a point between the condenser and the automatic switch, means controlled by said key for connecting the dialling equipment across the end of the trunk terminating in the automatic switch to operate the switch and for connecting the operator's headset across the other end of the trunk, means controlled by the key for establishing a direct current bridge across the end of the trunk terminating in the plug, means effective upon the actuation of the key and establishment of the last named bridge for maintaining said last named bridge upon the restoration of the key, and means effective upon the answering of the call set up over the automatic switch for opening said last mentioned bridge.

In witness whereof, I hereunto subscribe my name this first day of March, A. D., 1922.

BERNARD D. WILLIS.
